UNITED STATES PATENT OFFICE.

WILLIAM A. MACK, OF NORWALK, OHIO, ASSIGNOR TO THE STANDARD SEWING MACHINE COMPANY, OF CLEVELAND, OHIO, A CORPORATION OF OHIO.

BOBBIN-LATCH FOR SEWING-MACHINES.

SPECIFICATION forming part of Letters Patent No. 723,170, dated March 17, 1903.

Application filed December 26, 1893. Serial No. 494,635. (No model.)

To all whom it may concern:

Be it known that I, WILLIAM A. MACK, a citizen of the United States, and a resident of Norwalk, Huron county, State of Ohio, have 5 invented new and useful Improvements in Bobbin-Case Latches for Sewing-Machines, of which the following is a specification.

This invention relates to that class of sewing-machines employing a rotary or oscillating shuttle in which the bobbin and bobbin-case are removably contained, the object of the invention being to provide an improved latch of simple construction and operation for removably retaining the bobbin and bobbin-case in operative position within the shuttle and also for holding the bobbin-case in a non-rotatable position relative to the latter. This object I secure by means of the novel construction, arrangement, and combinations of parts, as hereinafter set forth in detail, and pointed out in the claims.

Referring to the accompanying drawings, forming part of this specification, Figure 1 is a front end elevation of the bed-plate of a sewing-machine provided with my improved latch, the latter being in closed or operative position relative to the bobbin-case. Fig. 2 is a plan view of the latch and its supporting-plate detached from the machine. Fig. 3 is 20 a front view of the same with certain of the parts broken away and in section. Fig. 4 is a vertical cross-section through certain of the parts, showing the relative positions of the latch and its holding device when the latch is in closed or operative position.

In the drawings, the bed-plate *a*, the rotary shuttle *b*, the shuttle-raceway casement *b'*, the bobbin *c*, and the bobbin-case *c'* are all of usual construction and arrangement, as 25 found in the "Standard" sewing-machine, to which in the present instance I have applied my improved bobbin-case latch. This latch comprises a horizontally-swinging bar, (indicated at *d*), which is pivoted at one end 30 to a supporting-block *d'* on the under side of the bed-plate and at its opposite or free end is movable to and from a position in front of the bobbin-case to hold the same in its position within the shuttle. As a simple and 35 convenient means for holding the latch in its

operative or closed position in engagement with the bobbin-case I have supported a pin *e* in a movable position within a pocket or opening in the block *d'*, with one end normally projecting below the under side of the latter in a position to engage with the latch at one side thereof and hold it in closed position, as shown. This pin *e* is supported to have a sliding movement within its opening in the block *d'*, so as to be movable to and from its 40 said normal position for engaging with the latch, the same being yieldingly held in such normal position by means of a spring *e'*, as shown in Fig. 3. By this arrangement of the holding-pin *e* when it is desired to remove 45 the bobbin and bobbin-case the operator will simply grasp the end of the latch and draw the same outwardly from its closed position, such movement of the latch operating to force the pin *e* upward and away from its holding 50 position relative thereto. To again close the latch after the bobbin and bobbin-case have been replaced in the shuttle, it is only necessary for the operator to push it to its closed position, as the pin is readily forced out of 55 the path of the latch during the movement of the latter thereunder. To insure the ready passage of the latch past the holding-pin in the manner described, the end of said pin is made somewhat pointed and the adjacent 60 sides of the latch beveled, as shown.

The bobbin-case, in addition to being retained within the shuttle, should also be held in a non-rotatable position therein. To effect this, I have provided the latch with an arm 65 *d*, which when the latch is in its closed or operative position is adapted to extend into an opening or recess *c* formed in the face of the bobbin-case and hold the latter against rotary movement, the end of said arm fitting 70 loosely within the opening or recess of the bobbin-case, so as not to interfere with the free passage of the needle-thread loop between the same.

When the latch is closed, it should engage 75 with the bobbin-case so loosely as to permit of the free passage of the needle-thread loop between the same. In order, therefore, to properly regulate the position of the latch relative to the bobbin-case when in its closed 80

position, I have provided the same with an adjustable stop, which engages with the shuttle-raceway casement or other stationary surface, as most clearly shown in Fig. 4, and limits the closing movement of the latch, this stop in the present case consisting of a screw d^3 , which is secured in a desired adjusted position relative to the latch by means of a jam-nut d^4 .

10. The block d' , by which the several parts comprising the latch mechanism are supported, is in the present case detachably secured in position on the under side of the bed-plate of the machine in order that the parts may be more conveniently assembled before being placed in position on the machine and also in order to permit of their more ready removal for the purposes of repair, adjustment, or otherwise.

20. What I claim as new, and desire to secure by Letters Patent of the United States, is—

1. In a sewing-machine, the combination, with a shuttle, bobbin and bobbin-case, of a swinging latch for retaining said bobbin-case in position and having means for holding the same against rotary movement, and a movably-supported catch device normally held in position for engaging with the latch to hold the same in its operative closed position, the said catch device being movable from its holding position by the engagement therewith of the latch upon the opening of the latter.
2. In a sewing-machine, the combination, with a shuttle, bobbin and bobbin-case, of a swinging latch for retaining said bobbin-case in position and having means for holding the same against rotary movement, a yielding-

supported catch device normally held in position for engaging with the latch to hold the same in its operative closed position, and means whereby said catch device may be moved from its normal position by the latch upon the opening and closing of the latter.

3. In a sewing-machine, the combination, with the shuttle, bobbin and bobbin-case, of a swinging latch for retaining said bobbin-case in position, an adjustable stop device carried by the latch for regulating its position relative to the bobbin-case, and means for holding the latch in its closed position, the said means being movable from holding position by the engagement therewith of the latch upon the opening of the latter.

4. In a sewing-machine, the combination, with the bobbin-case, of a swinging latch for retaining said bobbin-case in position, an adjustable stop device carried by the latch, and a spring-pressed pin for holding the latch in its closed position, the said pin being movable from holding position by the engagement therewith of the latch upon the opening of the latter.

5. In a sewing-machine, the combination, with the bobbin-case, of a swinging latch for retaining said bobbin-case in position and having oppositely-beveled sides adjacent to one edge thereof, and a longitudinally-movable spring-pressed pin having a tapering end for engaging with the beveled sides of said latch, for the purpose set forth.

WILLIAM A. MACK.
